UNITED STATES PATENT OFFICE.

AUGUST G. SANDMAN, OF BALTIMORE, MARYLAND.

END PLATE FOR FREIGHT CARS.

1,426,222.

Specification of Letters Patent. Patented Aug. 15, 1922.

Application filed August 19, 1921. Serial No. 493,524.

To all whom it may concern:

Be it known that I, AUGUST G. SANDMAN, a citizen of the United States, residing at Baltimore, in the State of Maryland, have 5 invented certain new and useful Improvements in End Plates for Freight Cars; and I do hereby declare the following to be a full, clear, and exact description of the invention, such as will enable others skilled in the art to which it appertains to make and use the same.

The invention relates to railway cars, and more particularly to metal end plates for freight cars of the box car type.

15 The principal object of my invention, generally considered, is to provide an exceedingly strong, simple and efficient pressed steel end for box cars and the like.

Another object of the invention is to provide a metal end of the corrugated type having means for rigidly uniting the same to the wooden structure of the car body at a plurality of points so as to adequately reinforce the end construction against abnormal pressure due to the shifting of the lading within the car.

Another object of the invention is to so arrange the metal in the end members as to thereby afford maximum strength without 30 materially increasing the weight of the said car ends.

A still further object of the invention is to so arrange the metal in a car end as to give maximum strength to resist a shifting 35 of the lading from the inside of the car as well as to provide an exceedingly strong construction to resist load or shock applied directly against the outside of the car end.

A still further object of my invention is 40 to provide means for rigidly uniting the metal end to the car bolster, said means being positioned so as to permit the removal and replacement of the side sheathing without cutting rivets or otherwise disturbing the car framework.

To these and other ends the invention comprises the various elements and combinations of elements hereinafter set forth, the novel features being pointed out in the 50 claims.

In the drawings, wherein I have illustrated several preferred embodiments of my invention,—

Figure 1 is a view in end elevation of a

freight car having a metal end embodying 55 the invention applied thereto.

Figure 2 is a section on the line 2—2 of Fig. 1, the section being viewed in the direction indicated by the arrows.

Figure 3 is a transverse vertical section of 60 a portion of the car end substantially as illustrated in Fig. 1.

Figure 4 is a view in side elevation of the construction shown in Fig. 1.

Figure 5 is a top plan view showing one 65 of the upper corner brackets, the car roof being removed.

Figure 6 is a section on line 6—6 of Fig. 4, the direction of view being indicated by the arrows.

70 Figure 7 is a view similar to Fig. 1, illustrating a modification.

Figure 8 is a section on line 8—8 of Fig. 7.

Figure 9 is a view in end elevation of another modification.

Figure 10 is a section on line 10—10 of Fig. 9, the direction of view being indicated by the arrows.

Figure 11 is a view in end front elevation 80 of a car illustrating another modification.

Figure 12 is a transverse vertical sectional view of the construction shown in Fig. 11.

Throughout the several views like parts are designated by like reference characters. 85

It might be here pointed out that I have illustrated in Figs. 1 to 6, inclusive, numerous details of construction which are adapted to be combined with the constructions shown in Figs. 7 to 12, inclusive, but 90 which are not illustrated therein, as it has been considered unnecessary to show in each of the modifications all of the various structural details. It is to be understood, however, that these details are in practice embodied in the structures shown in Figs. 7 to 12, inclusive.

95 Referring first to Figs. 1 to 6, inclusive, the numeral 1 designates a freight car provided with a metal end 2. The said car 1 is 100 furnished with a floor 3, inside sheathing 4, outside sheathing 5, corner posts 6, an end sill 7, a wooden inner end lining 8, a ridge pole 9, purlins 10, side members 11, a belt rail 12, a roof 13 fitting over and connected 105 to the ridge pole, side members and purlins, all as is usual in wooden box car construction.

In some of the various figures I have, for the sake of clearness, omitted the usual face plate or facia which fits between the roof 13 and the adjacent edge of the metal plate to close the opening 14.

In the construction shown in Figs. 1 to 6, inclusive, the metal end 2 is preferably formed from a plurality of plates 15, the web 16 of each plate being adapted to overlie the outer faces of the end or corner posts 6 and the end sill 7 and to conform to the outline of the car roof. The intermediate portions 16^a of each plate are preferably formed by compressing therein a series of convolutions or columns 17. It is to be observed that these depressions are formed on one side only of the web and extend the full distance between the outer face of the end lining 8 and the outer face of the end or corner posts 6. The intervening portions 18 between each convolution or column 17 preferably lie substantially in the plane of the outer face of the end sill 7. The inner face of each column 17 and the outer face of each intervening portion 18 is preferably flat, and these respective portions are also parallel and arranged in substantially the same respective planes.

The web 16 of each plate is preferably lapped around the side edges of the end or corner posts and overlies the adjacent portion of the outer sheathing 5 at the side edges of the car, as is clearly shown in Fig. 2. The web 16 at its lower portion is bolted to the end sill by means of a plurality of bolts 19, and is also securely connected to the end sill by means of the nuts 20 on the ends of the truss rods 21. Each plate 15 is also provided at its upper edge with an inverted flange 22 which underlies the purlins and ridge pole of the roof members. At the upper corners I provide angle braces 23 which overlie the front face of the web 16 and are preferably riveted thereto as well as to the rearwardly extending flange 24 of each plate. In order to rigidly unite the side members 11 to the adjacent plates 15 I provide angle brackets 25 which are riveted to the inturned upper flange 22 of each plate as shown in Fig. 5. These angle brackets are also provided with a downwardly extending flange 26 which lies in the plane of the angle brace 23 hereinbefore described, and bolts 27 are preferably employed to connect the brackets 25 and the braces 23.

At a point adjacent the belt rail 12 I provide another angle member 28 which is preferably riveted to the inner face of the web 16 of the adjacent plate by means of the rivets 29 and which is also riveted to the inturned flange 24 of each plate by the rivets 30. A thimble 31 is interposed between the flange 24 and the longitudinally extending portion of the angle 28 in order

to provide clearance for the outer sheathing 5. The angle member 28 extends in rear of the inner face of the end or corner post 6 and is riveted or otherwise secured to a plate member 32. This plate extends in an angular direction on the inner face of the sheathing, is gained into the side sill 33, extends below the same and is riveted or otherwise secured to the end of the body bolster 34.

At the lower corners of the car end I provide angle or corner brackets 35 which overlie the outer face of the adjacent portion of the plates 15 and are secured on their side faces to the side sills 33 by means of rivets 36. These corner brackets are also of course riveted to the outer face or web of each plate 15. I have shown in these figures end plates each substantially equal in area to one half of the car end, and in such construction I rivet the overlapped portions of the plates as clearly shown at 37 in Figs. 1 and 2. Preferably I interpose between the inner face of the portions 18 of each plate and the outer face of the inner lining 8, wooden nailing strips 38. These nailing strips, in addition to providing means for connecting the inner lining, form a reinforcing means for strengthening the end plates 15.

In Figs. 7 and 8 I have shown a plurality of plates 39 each provided with a plurality of inclined convolutions or columns 40, the central portions of each of said plates being adapted to form a half of a vertical convolution or column 41, the overlapping portions of the plates 39 being connected at 42 their overlapping portions by means of the rivets 42. The car construction in these figures is identical with that already described and in this modification also the web 43 of the plates 39 lies in the plane, or substantially in the plane, of the end posts and end sill, as hereinbefore described. The intervening portions 44 of the plates separating the columns or convolutions 40, are substantially in the plane of the webs and both the inner faces of the columns 40 and 41 and the outer faces of the intervening portions 44 are flat and substantially parallel. In this modification also there is interposed between the intervening portions 44 and the inner face of the end lining 8 the wooden nailing strips 38.

In Figs. 9 and 10 I have shown a further modification in which I employ a plurality of plates 45 each of which is furnished with a single vertically extending column or convolution 46, an inclined column or convolution 47, and a half vertical column 48, the half column of each plate being adapted to meet and overlap and to be secured together by means of the rivets 49. The inner faces of the columns 46, 47 and 48 are in direct contact with the outer face of the inner end lining 8, and these columns or convolutions are likewise formed on but one

side of the web 50 of the said plates. Except as above noted, the construction is the same as that hereinbefore described.

Referring now to Figs. 11 and 12, I have illustrated the plates 51 as being divided horizontally instead of vertically. Each of the plates 51 is furnished with a plurality of horizontally extending columns or convolutions 52 having flat inner faces bearing against the outer face of the end lining 8, the depth of these columns being substantially equal to the distance between the outer face of the end lining and the outer face of the end sill 7. The overlapping portions of the plates are connected by means of the rivets 53, and in this instance also the columns or convolutions are formed on one side only of the web 54 of each plate. Except as herein noted the construction is the same as has hereinbefore been described.

Having now described my invention, what I claim is:—

1. The combination with a car end framing, of a metallic end adapted to cooperate therewith, said framing including an inner lining, an end sill, a body bolster and corner posts, said metallic end comprising a plurality of metallic plates fitting over said corner posts and secured to said end sill, said plates each being furnished with corrugations whose depth is substantially equal to the distance between said inner lining and the front face of said end sill, and means for securing said metal end to said bolster, said means extending between each corner post and the adjacent side sheathing and being connected to the former.

2. The combination with a car end framing, of a metallic end adapted to cooperate therewith, said framing including an inner lining and an end sill, said metallic end comprising a plurality of plates each furnished with corrugations of substantially uniform depth having flat inner faces engaging said lining, the said corrugations projecting over said end sill and being in vertical alinement therewith, the portions of said plates intermediate the corrugations

lying substantially in the plane of the front face of the end sill, and means for securing said metallic end to said end framing.

3. The combination with a car end framing and including an end sill, of a metallic end therefor, said end comprising a plurality of plates each furnished with a web and a plurality of hollow columns formed in the said web and projecting only on one side thereof, the inner faces of said columns being parallel and arranged in the same plane, a portion of the web of said plates overlying the outer face of said end sill and means for securing said metallic end to said end framing, and means for connecting said plates to said end sills.

4. The combination with a car end framing, including an end sill, an inner lining and end posts of a metallic end member adapted to cooperate therewith, said end member comprising a plurality of metal plates having formed in the webs thereof and on one side only a plurality of columns, the inner faces of adjacent columns being flat and arranged in the same plane and engaging said inner lining, and means for securing said plates to said framing, said means including the car truss rods, the webs of said plates being adapted to overlie the front face of said end sill.

5. The combination with a car end framing, of a metallic end adapted to cooperate therewith, said framing including an inner lining and an end sill, said metallic end comprising a plurality of plates each furnished with vertical corrugations of substantially uniform depth, said corrugations forming columns projecting from one side only of said plate, the marginal edges of said plates lying in substantially the same plane, and means for connecting the adjacent portions of said plates to said end sill, the marginal edges of said plates lying in the plane of the front face of said end sill.

In testimony whereof I affix my signature.

AUGUST G. SANDMAN.
